UNITED STATES PATENT OFFICE.

ARTHUR C. LA MAY, OF ROCHESTER, NEW YORK, ASSIGNOR TO D. C. GILES, OF ELMIRA, NEW YORK.

CHEESE-CUTTER.

No. 821,175.

Specification of Letters Patent.

Patented May 22, 1906.

Application filed October 5, 1905. Serial No. 281,375.

To all whom it may concern:

Be it known that I, ARTHUR C. LA MAY, a citizen of the United States, residing at Rochester, in the county of Monroe and 5 State of New York, have invented an Improved Cheese-Cutter, of which the following is a specification.

This invention relates to cheese-cutters of that class in which the cheese is supported 10 upon a revoluble table provided with an operating-handle for rotating the table and a scale and stops for controlling the motion of the operating - handle so as to give to the table carrying the cheese any desired angular motion upon its center. In such machines there is usually arranged a knife having a vertical plane of motion, such knife arranged to be moved up and down for the purpose of cutting the cheese.

15 The essential features of my present invention consist in means for adjusting the height of the pivotal point or axis of motion of the cutting-knife, means for angularly adjusting the plane of the motion of the knife, together 20 also with means for adjusting the plane of the cutting-blade relatively to the plane of its motion.

A further feature of my present invention consists in the character of the limiting-stop 25 for controlling the movement of the handle which operates the cheese-carrying table.

Another feature consists in such an arrangement of the operating - handle that it may move inwardly and outwardly in a direction 30 practically radial to the revoluble cheese-carrying table and in the location on such operating-handle of a scale which is concealed except during the operation of the handle and the handle itself when in its closed position 35 forms no obstruction upon which articles may be caught and the cheese-carrying table accidentally operated.

Still another feature consists in the combination, with such handle as just before described, of a pawl-box guided independently of the cheese-carrying table and by or upon the frame of the machine and arranged to swing or move upon a center practically concentric with the center of the cheese-carrying table. 45 I provide also a spring-lock for holding the operating-handle in its inmost position.

50 By means of the above-enumerated features of construction I am enabled to overcome some of the difficulties present in

cheese-cutters as heretofore constructed, viz: 55 The operating-handle is not likely to be engaged and accidentally operated or moved. The pawl-box being supported and guided independently of the cheese - carrying table, there is no danger, in the backward or return 60 motion of such pawl-box, of carrying the cheese-table backward and there is less friction in such an arrangement. By providing for an adjustment in height of the pivotal support for the cutting-blade and also for an adjustment of the plane of motion of such cutting-blade and, still further, for an adjustment of the plane of the blade relative to its plane of motion I am enabled to compensate for any reasonable degree of wear in the blade and to 65 provide that the plane of motion of the blade shall always be vertical or, more properly speaking, at right angles with the plane of the cheese-carrying table and also for any desired degree of clearance to obviate any crowding 70 action of the knife in cutting the cheese, and I am also enabled thereby to provide that the plane of the blade shall always lie within the plane of its motion when desired.

I also provide an adjustable brake for opposing the rotation of the cheese-carrying board in order to retain the same in any position to which it may have been moved and afford an even and smooth resistance to its rotation.

85 The several drawings illustrating my invention are as follows: Figure 1 is a side view of one modification of my machine complete. Fig. 2 is a top view with the cheese-carrying board and knife removed. Fig. 3 is a sectional view taken along the dotted line $x\ y$ of Fig. 2 with the parts below and to the right of such line removed. Fig. 4 is a sectional view taken along the dotted line $x'\ y'$ in Fig. 2 and shows in detail the arrangement of 90 the adjustable brake. Fig. 5 is a sectional view taken along the dotted line $x^2\ y^2$ of Fig. 2 and shows the method of supporting the operating-slide from the under side of the radial arms of the base. Fig. 6 is a top view of 95 the base of the machine with all of the operating mechanism and knife removed. Fig. 7 is a top view of the operating mechanism. Figs. 8 and 9 are side and top views of a modification of my machine in which the knife-handle is conformed to encircle the base instead of continued from the top of the knife, as shown in Fig. 1. Figs. 10 and 11 are de-

tailed views of mechanism for retaining the adjustable stop securely in position and are taken, respectively, from the inside of the base and transversely through the center of such mechanism. Fig. 12 is an enlarged top view of the scale used on the operating-slide of the machine.

As seen in the several drawings, my machine consists, essentially, of the base B, supporting by suitable mechanism the cheese-carrying board B², upon which the cheese C is centrally located and prevented from moving angularly by means of the projecting blades c. The base B has a projection B¹, carrying the adjusting-screws s, supporting the bracket d, having arms d', forming the bearings of the knife K. This knife K is rigidly secured in a suitable handle and frame H, the left-hand end of which is extended into a flange f, suitably held by bolts b to the member a, pivoted on bolts b' in the upper ends of the arms d'. The bolts b pass through suitable clearances in the flange f to provide for an adjustment of the plane of the knife K relatively to the axis of the member a, so that the knife K may have more or less clearance, as desired, when making the cut through the cheese.

The bracket d is held securely upon the screws s by means of bolts b², as indicated. When it is desired to adjust the angle of the cut or the height of the knife relatively to the board B², the bolts b² are loosened and the screws s are adjusted from the under side of the base, and then the bolts b² are tightened. In this way the wear of the knife K may be compensated for. The base B has radial arms a' and a² extending inwardly and supporting at its center, by means of a bolt b⁴, the ratchet-wheel r, to which the cheese-board B² is secured by suitable screws passing through the holes r² in the arms r' of the wheel r. This wheel r is provided on its periphery with teeth for engaging a series of spring-pawls e', carried in a pawl-box e², supported by a radial arm e, pivoted on the bolt b⁴, by which the wheel r is operated. The pawl-box e² has formed on its left-hand side, as seen in Fig. 2, a lug e³, to which there is pivotally secured at p³ the right-hand end of the link w, the left-hand end of which is pivotally secured at p⁴ to the short arm of the lever u. This lever u is pivoted at p³ to an arm a³, connecting the base with the arm a². The longer arm of this lever u is pivotally connected at p' with the right-hand end of the link t, the left-hand end of which is pivotally connected at p with the left-hand end of the operating-slide k, supported from the under side of the arms a' and a² near the center of the base. As indicated in Fig. 5, the slide k is supported by a bar a⁵, separated from the arm a' by suitable blocks a⁴ a little thicker than the slide k and arranged to permit such slide to move freely between them.

The several parts are secured by suitable screws s' to the central portion of the arms a' and a², as indicated. The slide k extends through the front of the base, as indicated, and terminates in a finger-hold k'. As a result of the construction just described it will be observed that when the slide k is drawn out, as indicated by the dotted lines, the link t is moved to the right, the lever u is rotated to the left, the link w is moved to the left, and the arm e, carrying the pawl-box e², is rotated to the left upon the bolt b⁴, and the wheel r and the cheese-board B², carried thereby, are rotated to the left. From the short end of the lever u an arm u' extends downwardly and to the right, as seen in Fig. 2, and is arranged to pass under the link w and engage an adjustable screw-stop v', supported by the base B, as indicated. The head of this screw-stop v' is suitably graduated and arranged to coöperate with graduations on a fixed index v, so that such stop may be readily adjusted to any desired setting relatively to the arm u'. When the slide k is drawn out, it is moved until the arm u' engages the inner end of the stop v'. To facilitate the setting of the stop v', a suitable scale k² is secured upon the upper face of the slide k and is read by bringing the desired indication on such scale opposite to the outer edge of that part of the base directly over such slide k. To prevent the operation of the slide k when it is not desired to rotate the cheese C, a bell-crank lock n, pivoted at p⁶ to a lug a⁷, formed on the base B, is provided and carries at its left-hand end a projection arranged to engage the notch k³, formed in the slide k. This lock n is pivotally connected, as seen in Fig. 2, with a push-bar m, extending through the base B. A spring n' normally holds the lock n in engagement with the notch k³, and when it is desired to release the slide k the push-bar m is moved inwardly.

In order to provide an even resistance to the motion of the wheel r, a bent bar g of any suitable material is held firmly against a rabbit formed in the outer edge of the wheel r by means of the bolt b³ passing through the arm a', permitting an adjustment of the pressure upon the bar g exerted by the spring h, held between the arm a' and the nut on such bolt b³.

As seen in Figs. 3 and 6, a lug a⁶ is formed on the arm a² to support the outer end of the arm e and the pawl-box e².

As seen in Figs. 10 and 11, the adjustable screw-stop v' may be held in any desired adjustment by means of a split nut a⁸, secured by screws s² to the inside of the base B, as indicated.

A modified knife-handle is shown in Figs. 8 and 9, consisting in a ring H² of suitable metallic rod bent at its ends to pass into suitable holes in bosses f², formed on the flange f', to which the frame H' of the knife K is se-

cured. This flange f' is secured to the member a as already described by suitable bolts b . The ring or handle H^2 is secured in the bosses f^2 by means of suitable set-screws b^5 , as indicated. It will be observed that the handle H^2 is arranged to prevent the operation of the slide k when such handle is in its operated or downmost position, which is a condition to be desired, since the slide k ought only to be operated when the handle and knife are raised so as to clear the knife from the cheese.

The scale k^2 and adjustable screw v' are so graduated that one operation of the slide k will move the cheese C angularly, either a fixed weight of cheese or a fixed money value, as desired, according to the total weight of the cheese. For instance, if it is desired to sell a quarter of a pound of cheese for each operation of the slide k , the cheese is weighed before placing on the cheese-board B^2 , and then the adjusting-screw v' is regulated until the extreme outward motion of the slide k will bring the figure on the scale k^2 corresponding to the weight of the cheese just in line with the outside edge of the base B . Then each complete motion of the slide k will rotate the cheese-board B^2 angularly to the left, so as to cause one-quarter of a pound of cheese to pass by the knife K . Again, if it be desired to sell a certain definite money value of cheese for each operation of the slide k , after weighing the cheese the total return that must be made from the same is estimated. Then the adjusting-screw v' is regulated until this total amount on the scale k^2 comes in line with the outside edge of the base, when the slide k is in its extreme right-hand position. Then for each complete operation of the slide k a certain definite money value of cheese, say five cents worth, will be caused to move angularly to the left past the knife K . It will at once be understood that there is a definite and fixed relation between the readings on the graduated screw-stop v' and on the fixed index v for each desired angular motion of the cheese-table and that such screw-stop v' and such coöperating scales on the screw-stop v' and on the fixed index v constitute means for gaging and adjustably limiting the motion of the operating mechanism of my cheese-cutter independently of any scale on the slide k . The graduations on such screw-stop v' and index v may be arranged in any method according to any desired system to suit the convenience of the user. The graduations on the screw-stop v' and the index v may be used in accordance with any table, if desired, which may of course be made in accordance with the character of such graduations. Again, the graduations on the slide k may be of one denomination or of one character, while the graduations on the stop v' and the index v may be used to indicate the values of a different denomination. The operation of my machine

is believed to be so thoroughly obvious as to call for no further description herein.

What I claim is—

1. In a cheese-cutting machine, a base, a cheese-carrying board revolvably supported on such base, a cutting-blade, an arm for carrying such blade, a standard carrying a bearing fixed therein for such arm, and means for rigidly securing and adjusting such standard vertically on such base. 75

2. In a cheese-cutting machine, a revolvble cheese-carrying board, a cutting-blade pivotally supported to swing upon an axis practically parallel with the plane of the board and means for adjusting such pivotal support to vary the plane of motion of such cutting-blade relatively to the plane of such board. 80

3. In a cheese-cutting machine, a revolvble cheese-carrying board, a cutting-blade pivotally supported to swing upon an axis practically parallel with the plane of the board and means for adjusting such blade relatively to the plane of motion thereof. 85

4. In a cheese-cutting machine, a revolvble cheese-carrying board, mechanism for moving such board angularly on its center and for actuating such mechanism an operating element arranged to reciprocate in a direction practically radial to such cheese-carrying board. 90

5. In a cheese-cutting machine, a revolvble cheese-carrying board, mechanism for moving such board angularly on its center, for actuating such mechanism an operating element arranged to reciprocate in a direction practically radial to such cheese-carrying board and means for locking such operating element in its inmost position. 100

6. In a cheese-cutting machine, a revolvble cheese-carrying board, mechanism for moving such board angularly on its center, for actuating such mechanism an operating element arranged to reciprocate in a direction practically radial to such cheese-carrying board and a scale carried by such operating element arranged to be concealed within the machine when such element is in its inmost position. 105

7. In a cheese-cutting machine, a revolvble cheese-carrying board, mechanism for moving such board angularly on its center, for actuating such mechanism an operating element arranged to reciprocate in a direction practically radial to such cheese-carrying board, a scale carried by such operating element arranged to be concealed within the machine when such element is in its inmost position and means for locking such operating element in its inmost position. 115

8. In a cheese-cutting machine, a revolvble cheese-carrying board, mechanism for moving such board angularly on its center, for actuating such mechanism an operating element arranged to reciprocate in a direc- 120

125

130

- tion practically radial to such cheese-carrying board, a scale carried by such operating element arranged to be concealed within the machine when such element is in its inmost position, 5 means for locking such operating element in its inmost position and for limiting the motion of such operating element an adjustable screw-stop and coöperating therewith a member arranged to be actuated by such operating element.
9. In a cheese-cutting machine, a revolute cheese-carrying board, mechanism for moving such board angularly on its center, for actuating such mechanism an operating element arranged to reciprocate in a direction practically radial to such cheese-carrying board, means for gaging and limiting the motion of such mechanism comprising a threaded element and an element fixed relatively thereto, such threaded element and such fixed element carrying coöperating scales whereby the scale on such fixed member is adapted to gage the longitudinal travel of such threaded member while the angular motion of such threaded member is indicated by the scale thereon coöperating with a line on such fixed member parallel with the axis of such threaded member, and a scale carried by such operating element and arranged to be concealed within the machine when such element is in its inmost position.
10. In a cheese-cutting machine, a revolute cheese-carrying board, mechanism for moving such board angularly on its center

and for actuating such mechanism an operating element, such operating element carrying a scale arranged to be concealed within the machine when such operating element is at its zero or initial position. 35

11. In a cheese-cutting machine, a revolute cheese-carrying table, an operating device arranged to impart angular motion to such cheese-carrying table, a cutting-knife and a handle therefor and means for preventing the movement of such operating device 40 when the handle for such cutting-knife is in its downmost position.

12. In a cheese-cutting machine, a revolute cheese-carrying table, an operating device arranged to impart angular motion to 45 such cheese-carrying table, a cutting-knife and a handle therefor and means for preventing the movement of such operating device when such cutting-knife is down upon the cheese-carrying table. 50

13. In a cheese-cutting machine, a revolute cheese-carrying table and means for imparting angular motion thereto, a cutting-knife and a handle therefor, such handle connected to such knife by a member encircling 55 the machine on one or both sides and lying normally, when in its downmost position, in front of and below the plane of such cheese-carrying table.
